SUPPORTING BASE FOR ELECTRIC
SCISSORS

Malcolm S. Park, Mount Kisco, N. Y., assignor to
The Singer Manufacturing Company, Elizabeth, N. J., a corporation of New Jersey

Application April 18, 1942, Serial No. 439,469

4 Claims. (Cl. 30—231)

This invention relates to electric scissors and more particularly to supporting bases therefor, and has for its objective the provision of a relatively wide base which is readily and quickly attachable to electric scissors.

Another object of this invention is to provide a simple base which may be cheaply and readily manufactured and attached to electric scissors already in use, and which will permit the electric scissors to vibrate relative to the base without imparting vibration or noise thereto.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the accompanying drawing:

Fig. 1 is a top plan view of my improved base.
Fig. 2 is a side elevation of the base.

Fig. 3 is a vertical section of the base taken along the line 3—3 of Fig. 1 and showing the base attached to an electric scissors.

Fig. 4 is a sectional view taken along the line 4—4 of Fig. 1.

In the embodiment selected for illustration 10 represents a base made of sheet metal and having the shape of the sole of a sad-iron. To the under surface of the base 10 there is adhesively applied a layer of felt 11 which serves to prevent the base from scratching the table or support on which it may be placed. The upper surface is formed with a toe portion 12, which is struck up from the sheet metal base and has the shape of a toe-cap of a shoe. In rear of the toe portion 12 is a strap 13 which is also struck up from the metal base and in rear of the strap 13 and in alignment therewith is a rectangularly shaped slot 14, and near the rear end of the slot the base is formed with an overhanging inverted L-shaped lip 15.

Located on the rear or heel portion of the base 10 and in alignment with the toe and strap is a latch member 16 having an inverted U-shaped cross-section and formed with a longitudinal slot 17 and a protuberance 18 for easy manipulation by the finger. The latch member 16 is secured to the base 10 by means of the two rivets 19 and 20.

My improved base is adapted to be attached to electric scissors of the type illustrated and described in the patent to McArdle et al., No.

2,047,483, dated July 14, 1936. As shown in Fig. 3 of the drawing, the scissors are constructed with a frame 21 having a depending portion 22 to which is adjustably secured a lower blade holder 23 having a flange portion 24 and which carries a lower cutting blade 25. To the flange portion 24 there is secured by the rivets 26 a flat leaf spring 27 having resilient legs or rests 28 and 29. It will be understood that a vibratory upper blade 30 coacts with the lower blade 25 to sever the material.

To attach my improved base to scissors having the above described construction the end of the resilient rest 28 is inserted under the strap 13 and the scissors are pushed forward until the end of the rest is under the toe-cap 12. A slight pressure is then put on the scissors to place a tension on the rests 28 and 29, and at the same time the scissors are moved sideways until the rest 29 is in alignment with the latch 16 and the flange 24 is under the overhanging lip 15. When the scissors are in this position the flange or leaf spring support 24 has entered the slot 14 and the latch 16 is then moved from the full 20 to the dotted line position shown in Fig. 3, in which position the forward end of the latch 16 overlies the end of the rest 29 and the base locked to the scissors.

From the above it will be observed that the 30 scissors may be attached to and detached from the base readily, and with the minimum of effort, and that the connection between the base and the scissors is through the resilient spring 27. This construction permits the scissors to vibrate 35 freely relative to the base and allows the operator's hand to wobble sidewise relative to the base without disturbing the flat relationship of the base to the supporting table.

Having thus set forth the nature of the invention, what I claim herein is:

1. The combination with an electric scissors having a frame and a lower scissor blade support carried by said frame, of a flat base plate, means carried by said plate for detachably securing one 45 end of said blade support to said base and a manually operable latch mounted on and movable relative to said base plate to detachably connect the other end of said blade support to said base.
2. A base plate adapted to be attached to an electric scissors and having a toe-cap, an inverted L-shaped hold down, and a slideable heel-latch disposed at its upper side for its detachable connection to the spring legs of an electric 55 scissors device.

3. A base member for electric scissors having a lower blade support and a leaf spring rest secured at its central portion to the under side of the lower blade support, said base member comprising a flat blade having a slot in its upper face to receive the central portion of the leaf spring rest of the scissors, a strap located at one end of said slot under which one end of said leaf spring is adapted to be inserted and a manually operable device on said plate for releasably confining the other end of said leaf spring rest on said plate.

4. A base plate for supporting an electric scis-

sors having a blade support formed with a flange comprising, a plate having a pointed toe portion and a heel portion, a cap carried by the plate and located at the toe thereof, a latch located on the heel of said plate and slideable to and from said cap, a strap located adjacent said cap, a slot formed in said plate adjacent said strap, and a lip overhanging said slot, all of the above mentioned elements being located on the upper face of said plate and in a position to cooperate with the flanged blade support of said scissors.
